UNITED STATES PATENT OFFICE

2,196,062

NOZZLE DIAPHRAGM

John H. Doran, Scotia, N. Y., assignor to General
Electric Company, a corporation of New York

Application June 3, 1938, Serial No. 211,590

5 Claims. (Cl. 253—78)

The present invention relates to nozzle diaphragms such as are used in elastic fluid turbines for conducting elastic fluid to bucket wheels. More particularly, the invention relates to the

5 type of nozzle diaphragms which includes a nozzle structure having inner and outer bands and a plurality of spaced nozzle blades secured to the bands and forming nozzle passages for directing the flow of elastic fluid to a bucket wheel. The 10 inner band is usually united with a disk while the outer band is united with a solid ring.

An arrangement of this kind is disclosed in the patent to H. A. Lacey, No. 1,932,278, issued Oct. 24, 1933, and assigned to the same assignee 15 as the present application. The outlet edges of the nozzle blades are thin and when exposed to the high pressures and temperatures in modern elastic fluid turbines they are subjected to excessive strains and stresses which may lead to damage 20 of the thin outlet edges.

The object of my invention is to provide an improved nozzle diaphragm whereby the thin outlet edges of the nozzle blades are relieved from excessive strain. This is accomplished in accordance 25 with my invention by a nozzle diaphragm arrangement permitting expansion and contraction of the thin outlet portions of the nozzle blades without setting up therein excessive stresses. To this end the ends of the thin outlet 30 portions of the nozzle blades are secured to a resilient band or a resilient portion of a band.

For a better understanding of what I believe to be novel and my invention, attention is directed to the following description and the claims 35 appended thereto in connection with the accompanying drawing in which Fig. 1 is a sectional view through a turbine nozzle diaphragm and bucket wheel arrangement embodying my invention, Fig. 2 is a view along line 2—2 of Fig. 1 and Fig. 3 is a view along line 3—3 of Fig. 2.

The arrangement comprises a nozzle structure including a plurality of circumferentially spaced nozzles 10 with thin outlet edges 11 and with their inner ends secured to an inner band 12 and their outer ends secured to an outer band 13. Securing of the blades 10 to the inner and outer bands may be accomplished by a welding process as described in the aforementioned patent to Lacey. The inner band 12 is seated in 50 a recess 14 of a disk 15 and united with the latter by a weld 16. The outer band 13 is seated in a recess 17 of a solid outer ring 18 and united therewith by a weld 19. The nozzle diaphragm serves to conduct elastic fluid to a ring of buckets 55 21 on a bucket wheel 20 arranged in cooperative

relation with the diaphragm. Buckets 21 have their inner ends suitably fastened to a disk or wheel 22 and outer ends connected by a shroud band 23.

In order to prevent excessive strains and stresses from being set up in the thin outlet portions 11 of the nozzle blades 10, the end portions of the inner and outer bands 12 and 13 near said thin outlet portions 11 are made resilient. In the present example the end portions 10 24 and 25 of the inner and outer bands respectively are reduced in thickness and free to expand and contract in radial direction. In other words, these thin portions 24 and 25 are not secured to the solid disk 15 and the solid ring 18 respectively.

A simple method of producing such structure is first to form a structure of the conventional type with inner and outer bands 12 and 13 having outer cylindrical surfaces and completely 20 uniting these cylindrical surfaces with the disk and outer ring respectively, as shown in the aforementioned patent. Thereafter the thin free portions 24 and 25 of the inner and outer band respectively may be produced by machining 25 grooves 26 and 27 into the adjacent portions of the weld 16 and the inner band and the weld 19 and the outer band respectively. After manufacture the band 13 together with the weld 19 and the outer ring 18 form a unitary structure 30 secured to the outer ends of the nozzle blades 10. This unitary structure has a groove 27 to define a flexible or resilient member 25 connected to the thin outlet portions 11 of the blades 10. Likewise the disk 15 with the band 12 and the weld 16 may be considered as a unitary structure fastened or united with the inner ends of the blades 10 and having a flexible member or lip 24 united with the thin outlet portions 11 of the blades to avoid the setting up of excessive 35 stresses in said thin outlet portions during operation. The lips or thin portions 24, 25 are free to expand relative to the solid structures.

Having described the method of operation of my invention together with the apparatus which I now consider to represent the best embodiment thereof, I desire to have it understood that the apparatus shown is only illustrative and that the invention may be carried out by other means.

What I claim as new and desire to secure by 50 Letters Patent of the United States is:

1. Nozzle diaphragm comprising a nozzle structure with a plurality of nozzle blades having thin outlet edges and a band united with the ends of the blades, a solid member forming a seat for 55

- the nozzle structure and a weld uniting the band with the solid member, the band portion near the thin outlet edges of the blades being resilient and free to expand relative to the solid member.
2. Nozzle diaphragm comprising a plurality of spaced nozzle blades having thin outlet edges, inner and outer bands secured to the ends of the blades, said bands having portions reduced in thickness near the outlet edges of the blades, a disk forming a seat for the inner band, a weld uniting the inner band to the disk, a solid ring forming a seat for the outer band, and a weld uniting the outer band with the ring, the reduced portions of the bands being free to expand relative to the disk and the ring.
3. Nozzle structure for diaphragms comprising a band having an edge portion reduced in thickness to render such edge portion resilient, and a plurality of spaced nozzle blades with thin outlet portions having ends united with the band, the thin outlet portions of the blades being united with the reduced edge portion of the band to prevent breaking of the thin outlet portions of the blades when subject to high temperature changes.
4. Nozzle diaphragm comprising a plurality of spaced nozzle blades having thin outlet portions, and a unitary structure united with the ends of the blades, said unitary structure having a recess near the thin outlet portions to form a resilient member connecting the ends of the thin outlet portions to the unitary structure to prevent breaking of the thin outlet portions of the blades when subject to high temperature changes.
5. Nozzle diaphragm including a plurality of nozzle blades having thin outlet portions, and a rigid unitary structure having a resilient portion and connected to the ends of the blades with the resilient portion connected to the thin outlet portions of the blades to eliminate excessive strains and stresses in said thin outlet portions to prevent breaking of the thin outlet portions of the blades when subject to high temperature changes.

JOHN H. DORAN.
